[57] CLAIM

The ornamental design for a portion of a tongue for a buckle, as shown and described.

DESCRIPTION

FIG. 1 is a perspective view a portion of a tongue for a buckle showing my new design;

FIG. 2 is a top plan view thereof. The bottom plan view
thereof is a mirror image of FIG. 2;

FIG. 3 is a left side elevational view thereof;

FIG. 4 is a right side elevational view thereof;

FIG. 5 is a front elevational view thereof; and

FIG. 6 is a rear elevational view thereof.

In FIGS. 1—6, the dashed lines illustrate the remaining portion of a buckle.
